UNITED STATES PATENT OFFICE.

BERT DELL GILSON, OF CHICAGO, ILLINOIS.

MOTOR-PUMP ATTACHMENT.

1,340,389.

Specification of Letters Patent. Patented May 18, 1920.

Application filed March 12, 1919. Serial No. 282,100.

To all whom it may concern:

Be it known that I, BERT D. GILSON, a citizen of the United States, residing at Chicago, in the county of Cook and State of Illinois, have invented new and useful Improvements in Motor-Pump Attachments, of which the following is a specification.

The matters herein presented relate to an internal combustion engine, and the novel features particularly dwelled upon form portions of the water cooling system commonly employed in connection with such engine.

In a broad sense my aim is to accelerate the circulation through a cooling system of this character. More particularly my object is the provision of attachable devices for effecting such acceleration. Another object resides in the provision of flexible means for correcting inaccuracies in the alinement of the moving parts, when the device is attached to the somewhat imperfect clamping surfaces of the engine. Further objects and advantages will become apparent upon perusal of the following description and examination of the appended drawings, of which:

Figure 1 illustrates, in side elevation, an apparatus embodying the invention, as it appears mounted in practice.

Fig. 2 is a corresponding plan view of the apparatus.

Fig. 3 is an enlarged view of a portion of Fig. 1.

Figs. 4 and 5 illustrate important elements of the invention, and

Figs. 6 and 7 show a modified form of accelerating device.

Anyone versed in the art will notice that Figs. 1 and 2 illustrate portions of an internal combustion engine 1, and its radiator 2, both mounted on the framework of an automobile of the Ford type. The numeral 3 denotes the accelerating mechanism of my invention, and from this mechanism extends a shaft 4, said shaft having mounted on its outer extremity a pulley 5, which in turn is connected for rotation by the usual fan driving pulley 7 of the engine crank shaft 50 through the medium of the belt 6. The latter extends also over the pulley 8 of the fan 9, and the parts are so related that the fan and the accelerator shaft 4 are simultaneously rotated. The fan and fan pulley 55 are suspended on adjustable devices 10 for the purpose of taking up slack in the belt 6,

but as such devices, *per se*, are well known to the art, no further explanation is thought necessary.

In the waterjacket 11 of the engine is cut 60 an inlet port, and on the flange of the said port is bolted a member 12 of the accelerator 3. From the outlet port of the water jacket extends a flexible tube 13 to the upper portion of the radiator 2, and from the bottom 65 of the latter extends a tubular connection 14 to a coöperating member 15 of the accelerator. As the water within the jacket absorbs the heat of the engine it rises through the tube 13 and enters the radiator, 70 within which it gradually sinks, as it wastes its heat into the atmosphere, whereupon it is drawn through the tube 14 and back into the waterjacket.

While Fig. 1 of the drawings is not mechanically correct, it is drawn close enough to the proper proportions to indicate that the inlet port of the waterjacket is located considerably higher than the outlet 2^a of the radiator. Experience shows that, at least 80 on the well known type of engine considered, the circulation is not sufficiently rapid, and that consequent steaming of the radiator frequently occurs. This condition, of course, is detrimental to the engine. Referring now 85 to Fig. 3, it is noticed that the part 12 comprises, in addition to the bolting flange 12^a, a curved tube, which communicates with a substantially cylindrical chamber 12^b. The face of the said chamber and the face of the 90 accelerator member 15 are carefully machined, so as to form a watertight joint, and the parts are suitably bolted together. Operating within the chamber 12^b is a propeller member 16 (see also Fig. 5), which by suitable devices is fixed on an extension 4^a of the drive shaft 4, and is rotated by the said shaft in the direction indicated.

This propeller has on its periphery a plurality of blades 16^a, and the said blades, 100 instead of being axially placed, as is common in practice, are set at a certain angle, and this angle is nicely calculated in order to throw the water in the general direction of the channel 12. It may be remarked that 105 the said channel may be straightened by moving the flange 12^a to a position in alinement with the chamber 12^b, as shown in Figs. 6 and 7, but it has been found impossible to mount such a pump, large enough to 110 give entire satisfaction on heavy duty commercial vehicles of the type considered, on

account of the lack of room between the waterjacket and the part 17 of the engine support and hood.

The shaft 4^a is rotatably fixed in the member 15, and the latter has, at its outer extremity, a chamber 15^a, into which is threaded a packing gland 18, and suitable watertight packing is placed within the said chamber. A greasecup 19 may also conveniently be introduced for the purpose of lubricating the shaft 4^a. It is noticed that the water enters at 15^b, and that it passes through a chamber 15^c into the propeller chamber 12^b. The propeller 16 is made with narrow spokes 16^a, and it is noticed that it has, between its hub and peripheral flange, a chamber substantially of the same area as that of the chamber 15^c, and an uninterrupted passage for the water is thus provided. Attention is also called to the sleeve portion 15^b of the accelerator member 15. The said sleeve protects the shaft 4^a against the water and strengthens it against the upward strain of the propeller. A suitable end thrust washer 20 is also introduced.

Between the outlet flange 11^a of the water jacket and the flange 13^a of the tube 13 is clamped a bracket 21, and the latter terminates in a journal box 21^a, within which the shaft 4 is rotatably fixed. It would be quite impossible, commercially speaking, to mount this bracket 20 and the accelerator 3 in good enough alinement to rotatably support the shaft 4, 4^a, and experience has shown that, even though the parts be fairly well alined in the first instance, they soon become shaken out of line. In order to overcome this difficulty I have introduced flexible devices at the juncture of the shaft members. In the drawings I have illustrated a very simple form of flexible coupling, comprising merely a coil spring 22 having its ends anchored in the abutting ends of the shaft members. The spring 22 also illustrates another important feature. As the distance between the accelerator and the bracket 21 will vary on every machine, the spring will adjust itself to the variation. But I wish it understood that I may substitute more elaborate devices, having a wider range of flexibility.

In mounting the accelerator the horn has been removed from its usual support. In order to reestablish it in substantially its former position, a flange 12^c is made to extend upwardly from the member 3, and this flange is perforated to receive the clamping screws of the horn 23.

In Figs. 6 and 7 I show a very much smaller accelerator, for use on light pleasure vehicles. It consists of two members 24 and 25, and the former terminates in a flange 24^a for attachment to the water jacket, as already explained in connection

with the large accelerator. The propeller chamber is in this case formed by equal portions of the members 24 and 25, and its width is merely sufficient to afford the propeller operating space. The said propeller is not concentrically positioned within the chamber, but is placed close to the wall nearest the outlet and well to the top of the chamber so as to trap as much as possible of the water during the upward rotative motion, and to throw this water by centrifugal force toward the outer periphery of the chamber. The arrows in Fig. 7 indicate how the water enters the chamber, and also the general direction in which the water is propelled. A groove 25^a starts near the top of the chamber and increases uniformly in size until largest at the outlet 25^c, and this groove, by affording the water more escaping space, materially reduces friction and thereby adds to the efficiency of the pump. The vanes 26^a of the propeller are curved rearwardly, relative to the direction of rotation, in order to induce increased centrifugal action on the water, and experience has shown me that this shape of propeller, placed in a chamber of the form presented, gives the very best results. In order to strengthen the vanes of the propeller I provide a narrow tie-band 26^b, having an opening corresponding to the inlet port in size, and the said band bears against the wall of the chamber, whereby the friction of vanes rubbing against the wall is eliminated. A drain 25^d is provided in order to prevent water remaining in the pump, when not in use.

I claim:

1. The combination with a motor and its water jacket, a radiator and crank shaft, of a pump attachable to and communicating with the said water jacket, a propeller shaft extending from the said pump, a journal bracket attachable to the front end of the motor and supporting the front end of the said shaft, devices for rotatably connecting the shaft with the said crank shaft, and devices for rendering flexibility to the said propeller shaft intermediate the said bracket and pump.

2. A circulation accelerating attachment for a motor car including a pump and a propeller shaft extending from the said pump, a front bearing bracket, said bracket supporting a drive shaft in continuation of the said propeller shaft, and flexible shaft-interconnecting devices compensating for imperfect alinement of the parts.

3. A circulation accelerator attachment including, a pump and a propeller eccentrically positioned within the pump so as to trap the incoming water and to lift it and throw it by centrifugal force into a funnel shaped outlet channel, a drain at the bottom of the said pump, a drive shaft sup-

- ported in detachable devices in front of the pump, and flexible elements operatively connecting the said drive shaft with the propeller.
- 5 4. A circulation pump having an extending propeller shaft, a drive shaft detachably mounted in front of the said pump, and a coil spring having its ends seated in perforations of the said shafts, thereby forming a flexible and alinement compensating connection between the shafts, all for the purpose set forth.
- 10 5. A water circulation accelerating attachment for a motor car including, a pump having an offset outlet channel, a propeller within the said pump and having blades twisted so as to direct the water through the said channel, a drive shaft detachably hung and positioned to operate the said propeller, and compensating devices connecting the 20 said shaft to drive the said propeller.
6. In a circulating pump attachment, a drive shaft, a propeller shaft, alinement compensating elements interconnecting the said shafts, a propeller rigid on the free end 25 of the said propeller shaft, a propeller housing having a cylindrical inlet chamber concentric with and encompassing the propeller shaft adjacent to the said propeller, and an annular supporting band interconnecting the propeller vanes, said band having its central opening corresponding in size with the said inlet chamber, so as not to obstruct the passage through the housing.
- 15 In testimony whereof I have hereunto af- 30 fixed my signature.
